UNITED STATES PATENT OFFICE.

WILLIAM SAMUEL RINGSTAFF, OF HICKORY, NORTH CAROLINA.

HARNESS.

No. 916,599.

Specification of Letters Patent. Patented March 30, 1909.

Application filed May 28, 1908. Serial No. 435,565.

To all whom it may concern:

Be it known that I, WILLIAM SAMUEL RINGSTAFF, a citizen of the United States, residing at Hickory, in the county of Catawba and State of North Carolina, have invented new and useful Improvements in Harness, of which the following is a specification.

This invention relates to harness, the object in view being to provide shaft supporting means so constructed and related to the harness saddle as to do away with the greater portion of the stitching now necessarily resorted to in the manufacture of harness while providing a strong, practical and reliable structure which will admit of the necessary adjustment to animals of different sizes.

With the above and other objects in view, the nature of which will more fully appear as the description proceeds, the invention consists in the novel construction, combination and arrangement of parts as herein fully described, illustrated and claimed.

In the accompanying drawings:—Figure 1 is a side elevation of a harness saddle showing the supporting means of this invention applied thereto. Fig. 2 is a partial front elevation of the same partly in section. Fig. 3 is an enlarged detail perspective view of sling. Fig. 4 is a detail perspective view of the eye members. Fig. 5 is a similar view of the buckle. Fig. 6 is a perspective view of the yoke piece. Fig. 7 is a side elevation of the device as applied to double harness. Fig. 8 is a vertical sectional view of the same.

Referring to the drawings, 1 designates the ordinary harness saddle which may be of any usual or preferred construction and provided at opposite sides with attaching eyes or loops 2 for the attachment of the supporting strap 3.

4 designates the protector strap which extends from the saddle downward and lies inside of the supporting strap 3.

5 designates a sling either for supporting a shaft or a trace according as to whether the same is used on single or double harness. This sling is best illustrated in Fig. 3 and is composed of a stout piece of leather of several thicknesses stitched together along the marginal edge, the extremities of such slings being disposed uppermost and provided with cross slots 6 which adapt the ends of the sling to be pushed over the oppositely pro-

jected loops 7 of a yoke disk or body which is in the form of a disk shown at 8 provided with holes 9 adapted to receive rivets by which the yoke piece is securely connected to one end or the other of the sling 5, the disk shaped body lying between the ends of the sling while the loops 7 project on opposite sides of the ends of the sling to receive portions of the supporting strap 3 which is shown in Figs. 1 and 2.

The opposite ends of the supporting strap 3 are secured to a buckle which is illustrated in detail in Fig. 5 where it is seen to comprise the opposite parallel side bars 10, the connecting body or web 11 which is provided with studs 12 arranged at a suitable distance apart, the buckle also comprising the end cross bars 12' which are offset to one side of the plane of the body 11 to allow of the passage of the ends of the strap beneath the cross bars 13. One end of the strap is provided with holes to receive the studs 12 and is thereby secured to the buckle. The strap is then passed around beneath the sling 5 and upward beneath the cross bars 13 of the buckle thence upward through a strap loop 14 on the saddle 1, then through the eye or ring 2 on the saddle, then downward again through the strap loop 14 to the buckle 10 where the end of the strap is secured to the buckle by providing the same with other holes to receive the studs 12 all as clearly shown in Fig. 2. In this way, the sling 5 is securely supported by the strap 3.

Secured to the lower end of the sling 5 is an eye best illustrated in Fig. 4 wherein it is seen to comprise a base plate 15 provided with rivet holes 16 adapting the same to be secured to the sling, and an eye 17 which is adapted to receive the upper bight of an adjusting or tightening strap 18 which passes through the upper end of the frame of a buckle 19 to which is connected one extremity of the girth strap or pulley band 20, the strap 18 being provided with an adjusting buckle 21 to take up slack therein and tighten the pulley band in order to secure the harness saddle firmly upon the back of the animal.

In utilizing the invention in connection with double harness as shown in Figs. 7 and 8, the sling 5 may be made considerably shorter, being just large enough to admit of the passage therethrough and admit of one of the traces shown at 22. The trace also has

secured thereto a stay 23 which is secured at intervals to the trace by rivets or like fasteners 24 provided with spaces between such fasteners to receive the sling 5. In Fig. 7 the sling 5 is shown as arranged between the innermost fasteners 24 and for a larger or smaller animal, said cylinder may be adjusted to either of the outer spaces as may be found necessary.

10 In Figs. 7 and 8, 25 designates the saddle which is provided at its opposite ends with rings 26 to receive the supporting strap 3, otherwise the construction is the same as that shown in Figs. 1 and 2.

15 I claim:—

1. The combination with a harness saddle, of a sling embodying a flexible strap bent upon itself with the two ends thereof arranged uppermost and provided with cross 20 slots, a yoke piece having the body thereof arranged between the ends of the sling and provided with oppositely extending loops which pass through the slots of the sling and project on opposite sides of the sling, a supporting strap 25 connected with the saddle and passing around said sling and through the loops of the yoke piece, means for securing the ends of said supporting strap, a trace adapted to pass through said sling, and a stay in the form of a strap extending lengthwise of a portion of the trace and secured thereto at intervals by fasteners leaving intervening spaces for the reception of a portion of the sling, substantially as described.

loops of the yoke piece, and means for securing the ends of said supporting strap.

2. In harness, the combination with a harness saddle, of a sling for the purpose 30 specified, a yoke piece having the body thereof interposed between opposite portions of the sling and provided with oppositely projecting loops which project on opposite sides of the sling, a supporting strap 35 connected with the saddle and passing around said sling and through the loops of the yoke piece, means for securing the ends of said supporting strap, a trace adapted to pass through said sling, and a stay in the 40 form of a strap extending lengthwise of a portion of the trace and secured thereto at intervals by fasteners leaving intervening spaces for the reception of a portion of the sling, substantially as described. 45

In testimony whereof I affix my signature in presence of two witnesses

WILLIAM SAMUEL RINGSTAFF.
